CLAIM

The ornamental design for a high pressure cleaning apparatus, as shown and described.

DESCRIPTION

FIG. 1 is a front, right, top perspective view of a high pressure cleaning apparatus, showing my new design; FIG. 2 is a rear, light, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top elevational view thereof; and, FIG. 8 is a bottom elevational view thereof. The dashed broken lines in the figures illustrate portions of the high pressure cleaning apparatus that form no part of the claimed design.
